FLAME DETECTOR

Ross S. Marsden, Jr., Bartlesville, Okla., assignor to Phillips Petroleum Company, a corporation of Delaware

Application June 13, 1952, Serial No. 293,480

12 Claims. (Cl. 340—228)

This invention relates to flame detection devices for use in combustion apparatus. In another aspect it relates to an improved flame detecting element.

In various jet type engines considerable difficulty has been encountered in detecting the presence of flame in particular regions of the engine. If flame is permitted to extend beyond the normal combustion chamber, damage may result from the flame impinging upon elements not capable of withstanding the high temperatures or from chemical reactions of reactive gases present within the flame. A flame containing reactive gases can erode away very rapidly metallic parts and even some non-metallic parts of the engine. An intermittent flame bath is especially destructive in this regard. While various arrangements have been proposed in the past for the detection of flame, for the most part, these devices are of the thermocouple or thermostat type and dependent upon the heat generated by the flame to give an indication of the flame. These devices thus indicate temperature rather than flame, and as such are not entirely reliable.

It is toward overcoming the difficulties inherent in the prior art flame detection devices that the present invention is primarily concerned. To this end there is provided an improved type of flame detector which is responsive to the presence of flame impinging upon an element disposed in the region of the flame being detected. This improved detector gives a rapid response to the presence of flame but does not produce a signal in the absence of flame, that is, the element is not responsive to temperature changes.

Accordingly, it is the object of the present invention to provide an improved flame detector capable of providing a rapid response to flame impinging thereon.

Another object is to provide a flame detector capable of distinguishing between flame and high temperatures which may be produced by a flame.

A further object is to provide a flame detector of simple, rugged construction which is capable of withstanding prolonged contact with high temperature flame.

Various other objects, advantages and features of this invention should become apparent from the following detailed description taken in conjunction with the accompanying drawing in which:

Figure 1 is a schematic view, shown partially in section, of the flame detection apparatus of this invention employed in conjunction with a turbojet aircraft engine;

Figure 2 is a fragmentary view of a portion of a combustion chamber containing a modified flame detection element; and

Figure 3 is a fragmentary view of a portion of a combustion chamber containing a second modified flame detection element.

Referring now to the drawing in detail and to Figure 1 in particular, a turbojet aircraft engine is represented schematically. This engine comprises a casing or housing 10 of essentially circular cross section having an air intake 11 and a discharge nozzle 12. Proceeding from the inlet end to the outlet end, casing 10 contains an air

2

compressor 13, a plurality of combustion chambers 14 arranged annularly around the engine at equally spaced intervals and a gas turbine 16. Air supplied by compressor 13 is employed to support combustion of a liquid fuel injected into combustion chambers 14 through fuel nozzles 17 which are fed by a fuel line 18. The greatly expanded volume of resulting heated gases is fed through turbine 16 and thence outwardly through discharge nozzle 12. The purpose of turbine 16 is to drive air compressor 13 through a shaft 20 connecting the rotor assembly of turbine 16 with the rotor assembly of air compressor 13. Turbine 16 includes a peripheral set of stationary vanes 22 and a movable set of blades 23 disposed adjacent thereto. Located centrally within the tail pipe of the engine is a discharge air regulating plug 25 which is suspended therein by appropriate structure, not shown.

For satisfactory operation of such a turbojet engine it is necessary that the fuel-air ratio supplied to combustion chambers 14 be regulated so that flame produced within these chambers is not of such length as to impinge upon vanes 22 or blades 23 of turbine 16. This is important because flame impinging upon these elements will greatly reduce the fatigue strength thereof. Vanes 22 and blades 23 normally are constructed of an alloy steel which is not capable of withstanding prolonged contact with flame. It is, therefore, desirable that means be provided to detect the presence of flame in the region adjacent vanes 22. By positioning a flame detecting element immediately forward vanes 22, suitable adjustment of the fuel and air supplied to combustion chambers 14 can be made as necessary to prevent flame from impinging upon said vanes.

The flame detecting element provided in accordance with this invention comprises a probe 30 disposed immediately forward vanes 22 in each of the combustion chambers 14. Probe 30 consists of an electrode which is mounted in the wall 31 of chamber 14 by means of a suitable insulating support 32. Electrical leads 34 are connected to probes 30 and pass through insulating sheaths 35 mounted in casing 10. Leads 34 are joined and connected through a capacitor 39 to one input terminal of a high gain alternating current amplifier 38, the second input terminal of which is maintained at ground potential. The walls of combustion chamber 14 are maintained at ground potential and a resistor 40 is connected between leads 34 and ground. The output terminals of amplifier 38 are connected to a suitable current responsive device 41.

It has been discovered in accordance with the present invention that if an electrical conductive probe is disposed in the region of a flame, fluctuating voltages are generated across an impedance element connected between the probe and a point of reference potential by flame impinging upon the probe. It is known that a flame forms an electrically conductive path which is believed to be established by ions present in the flame. It is thought that the impingement of these ions on the probe element disposed in the flame serves to generate the above-mentioned fluctuating voltages. The detector of this invention is particularly effective for indicating turbulent flames.

Probe 30 is constructed of a material which is both electrically conductive and capable of withstanding prolonged contact with high temperature flames without disintegrating. To this end, probe 30 can be constructed of a non-corrosive metal such as stainless steel, for example. For the detection of extremely high temperature flames, however, it is preferable to employ a ceramic such as silicon carbide or a ceramic coated metal such as siliconized molybdenum. Insulating support 32 can be constructed of any material capable of withstanding the high temperatures encountered in combustion chambers. Suitable materials for this purpose include aluminum oxide, magnesium oxide and porcelain. Although silicon car-

bide normally is considered to be an electrical insulator, at elevated temperatures the electrical resistivity of silicon carbide is lowered considerably, such that it can be considered electrically conductive. The following table illustrates the electrical resistivity of selected materials at 1000° C.:

Material:	Electrical resistivity (ohms/cm. cubed)
Carborundum brick (silicon carbide)	4.1
Bauxite brick (aluminum oxide)	17,200
Chemical porcelain	20,000
Periclose (magnesium oxide)	Infinite

The above values were obtained from "Refractories," F. H. Norton, McGraw-Hill Book Company, Inc., New York, third edition, 1949, page 556.

The foregoing list of materials, however, should be considered as being illustrative only, because the present invention is not limited to any particular probe or insulator material. Any substance which is an electrical conductor at the temperatures encountered can be employed for the probe element, and any material which is an electrical insulator can be employed to insulate the probe from the walls of the combustion chamber.

In Figure 2, there is shown a modification of the probe element in which a probe 40 is illustrated as extending between the opposite walls of combustion chamber 14 and being mounted on both of said walls by respective insulating supports 32 and 42.

A third modification of the probe element is illustrated in Figure 3 in which a probe 46 is formed substantially flush with the inner surface of wall 31 of combustion chamber 14. The three illustrated embodiments show that the probe element can take various forms, the only requirement being that a portion of the probe be disposed in the region of the flame being detected.

For purposes of illustration the present invention has been described in conjunction with a turbojet aircraft engine. The exact details of this engine are, of course, not essential to an understanding of the invention, and it is not intended to limit the invention to any particular form of combustion chamber. The probe and associated circuitry can be employed as a flame detector completely independent of any particular combustion chamber. The essence of the invention comprises a probe and means for detecting fluctuating voltages generated between the probe and a point of reference potential by flame impinging upon the probe. In the illustrated arrangement, this point of reference potential conveniently is the grounded wall of the combustion chamber. The output electrical signal from amplifier 38, in addition providing an indication of flame, can actuate various control systems or warning devices as is well understood by those skilled in the art.

While the present invention has been described in conjunction with present preferred embodiment thereof, it is to be understood that this description has been illustrative only and not as a limitation of the invention.

What is claimed is:

1. Flame detecting apparatus comprising, in combination, an electrode adapted to be positioned in the region of flame, an alternating current amplifier, means connecting the respective input terminals of said amplifier to said electrode and to a point of reference potential, said means including filter means to block the passage of unidirectional current flow, and means connected to the output terminals of said amplifier to detect the output signal of said amplifier, which signal is a function of the fluctuating potential developed between said electrode and said point of reference potential solely by flame impinging upon said electrode.

2. Apparatus for detecting flame in a combustion cham-

ber comprising, in combination, an electrode positioned in said chamber and electrically insulated therefrom, an alternating current amplifier, means connecting the respective input terminals of said amplifier to said electrode and to a point of reference potential, said means including filter means to block the passage of unidirectional current flow, and means connected to the output terminals of said amplifier to detect the output signal of said amplifier, which signal is a function of the fluctuating potential developed between said electrode and said point of reference potential solely by flame impinging upon said electrode.

3. The combination in accordance with claim 2 wherein in said electrode is secured to but electrically insulated from a wall of said combustion chamber, said electrode being substantially flush with the interior surface of the wall of the combustion chamber to which said electrode is secured.

4. The combination in accordance with claim 2 wherein in said electrode comprises a bar of electrical conductive material secured to but insulated from a wall of said combustion chamber, said bar extending into the interior of said combustion chamber.

5. The combination in accordance with claim 4 wherein in said bar extends substantially across said combustion chamber.

6. Apparatus for detecting flame in a combustion chamber comprising, in combination, an electrode positioned in said chamber, a mounting support of electrical insulating material securing said electrode to a wall of said combustion chamber, an alternating current amplifier, means connecting the respective input terminals of said amplifier to said electrode and to a point of reference potential, said means including filter means to block the passage of unidirectional current flow, and means connected to the output terminals of said amplifier to detect the output signal of said amplifier, which signal is a function of the fluctuating potential developed between said electrode and said point of reference potential solely by flame impinging upon said electrode.

7. The combination in accordance with claim 6 wherein in said electrode is constructed of stainless steel.

8. The combination in accordance with claim 6 wherein in said electrode is constructed of silicon carbide.

9. The combination in accordance with claim 6 wherein in said electrode is constructed of siliconized molybdenum.

10. The combination in accordance with claim 6 wherein in said mounting support is constructed of aluminum oxide.

11. The combination in accordance with claim 6 wherein in said mounting support is constructed of magnesium oxide.

12. The combination in accordance with claim 6 wherein in said mounting support is constructed of porcelain.
